UNITED STATES PATENT OFFICE.

ROBERT CRAWFORD JOHNSON, OF LEICESTER, ENGLAND.

RUNNER FOR CURTAIN RODS.

Application filed March 26, 1925, Serial No. 18,372, and in Great Britain July 16, 1924.

This invention relates to wheeled runners for curtain rods of the kind comprising a bar or rod extending across or around the window or recess to be screened and on one edge of which are supported the runners carrying the curtain or curtains, one or more of the runners, termed master or leading runners, having a cord or the like connected thereto for moving it or them when drawing the curtain or curtains aside, the said master-runners coming into contact with and moving the other or ordinary runners.

The object of my invention is to enable an ordinary runner to be converted at will into a master-runner and vice versa and to this end I provide a separate member designed to be detachably connected to the runner and carrying an attachment for the reeving cord.

In a suitable arrangement for carrying out the invention the separate member is made in the form of a cap designed to slip on to and fit upon one end of the runner, the attachment for the reeving cord being in the form of a rod loosely carried in a hole in a lug on the cap so as to hang therefrom and swivel thereon, the rod having a spherical or bulbous head at its upper end, whilst its lower end screws into a block having a hole for the passage of the reeving cord which can be pinched in the hole by rotation of the rod.

To enable the invention to be fully understood I will describe it by reference to the accompanying drawing, in which:—

Figure 1 is a front view of an ordinary runner converted into a master-runner by means of a separate member in accordance with the invention and mounted in position on a curtain rod.

Figure 2 is a sectional view at right angles to Figure 1 showing the curtain rod supported in position on a window frame or other surface.

Figure 3 is a front view of the ordinary runner and separate member, separated.

Figures 4, 5 and 6 are, respectively, a rear view, a side view and a plan view of the separate member.

a is the curtain bar or rod attached to a window frame or other surface *A* through the medium of a series of distance-pieces *b* and screws *c* one only of each of which is shown in the drawing.

d is the ordinary runner for supporting a curtain by the hook *d* and *e*, *e* are rollers

pivoted thereto and bearing against the edges of the bar or rod *a* to enable the said runner to be easily traversed along the said bar or rod. *f* is the separate member in the form of a cap designed to fit on the upper end of the runner *d* to convert it into a master-runner, *g* being the rod attachment for the receiving cord *h*, loosely carried in the hole *i* in the lug *j* on the cap *f* and having the spherical or bulbous head *k* at its upper end. *l* is the block into which the lower end of the rod *g* screws and *m* is the hole in the said block for the passage of the reeving cord, the latter being secured to the said block by being pinched by rotation of the rod *g* in the screwed hole in the said blocks.

Claims:

1. The combination with a supporting rod and ordinary runners slidable thereon, of a separate reeving member provided with means for attaching a reeving cord thereto, and with attaching means for detachably securing it to an ordinary runner, and said ordinary runners each being provided with a portion to be engaged by said attaching means for detachably securing said reeving member in operative relation therewith, whereby said reeving member may be placed in operative engagement with one or other of said ordinary runners to convert it into a master runner, and may be removed therefrom, without disengaging the reeving cord from said separate reeving member.

2. The combination with a supporting rod and ordinary runners slidable thereon, and each provided with vertically disposed portions projecting above the rod, of a separate detachable member comprising a cap adapted to fit upon the said vertically disposed portions of any of said ordinary runners, and provided with a depending portion having means for securing it to a reeving cord, to convert the ordinary runner with which said member is placed in engagement into a master runner.

3. The combination with a supporting rod and ordinary runners slidable thereon, of a separate reeving member provided with an aperture to receive a reeving cord, and a clamping device to clamp the reeving cord, adjustable with respect to the reeving member, said separate reeving member and said ordinary runners being provided with interengaging portions whereby said reeving member may be detachably connected with any one of the ordinary runners to convert

it into a master runner, or detached therefrom without detaching the reeving cord from said detachable member.

4. The combination with a supporting rod and ordinary runners slideable thereon, of a separate member provided with means for detachably engaging any one of the ordinary runners, said member being provided with a rotatable supporting rod loosely connected therewith, and depending therefrom, and having a threaded portion, and a clamping and supporting block, provided with a horizontal aperture for receiving a reeving cord, and a vertical threaded aperture communicating therewith to receive the threaded portion of said rod, and enable the reeving cord to be clamped thereby in said aperture.

5. The combination with a supporting rod

and ordinary runners slideable thereon, and each provided with vertically disposed portions projecting above the rod, of a separate detachable member comprising a cap adapted to fit upon the said vertically disposed portions of any of said ordinary runners, and provided with a horizontal perforated lug, a vertically disposed rotatable rod loosely engaging said aperture and provided above the lug with an enlargement, and provided at its lower end with a threaded portion, and a block having a horizontal aperture to receive a reeving cord, and a vertical threaded aperture communicating therewith, for supporting the block and permitting the reeving cord to be clamped in relation thereto.

ROBERT CRAWFORD JOHNSON.
